UNITED STATES PATENT OFFICE.

EUGENE T. TURNER, OF DAVENPORT, IOWA, ASSIGNEE TO AMERICAN PNEUMATIC ACTION COMPANY, OF DAVENPORT, IOWA, A CORPORATION OF WEST VIRGINIA.

TRACKER MECHANISM FOR PIANO-PLAYERS.

1,056,858.

Specification of Letters Patent.

Patented Mar. 25, 1913.

Application filed September 22, 1911. Serial No. 650,824.

To all whom it may concern:

Be it known that I, EUGENE T. TURNER, a citizen of the United States, residing at Davenport, in the county of Scott and State of Iowa, have invented a new and useful Tracker Mechanism for Piano-Players, of which the following is a specification.

My invention relates to improvements in piano players in which a perforated roll is passed over a series of apertures so that the perforations in the roll coming in coincidence with the apertures cause the said apertures to be opened and closed. The portion of the mechanism which contains the apertures is termed the tracker board. In preparing the rolls the location of the perforations upon them are not always uniformly located and occur at varying distances from the edge of the roll.

My invention has for its objects, the provision of mechanism for securing the accurate alinement or registration of the perforations in the music roll with the apertures in the tracker and the further object of supplying a means for adjusting the mechanism so as to accommodate it to music rolls in which the apertures are located at different distances from the edge of the roll. I attain these objects by the mechanism illustrated in the accompanying drawings, in which:

Figure 1 is a front elevation of my invention partially in section; Fig. 1^a is a detail of Fig. 1 in longitudinal section; Fig. 2 is a sectional detail of the mechanism for adjusting the location of the spool for the music roll, and Fig. 3 is a partial end elevation of the pneumatic.

Similar reference letters refer to similar parts throughout the several views.

The reference numerals 1 and 2 designate the side bars which are secured vertically in the piano and in which are journaled, one above the other, the music spools, 3 and 4. The music rolls are supplied permanently secured to a spool which must be inserted in the player, and upon which the piece is rewound after being played. In order to receive this music spool upon which the roll is permanently attached, I have provided in the upper portion of the side bar a journal, 5, in which is mounted, so as to both rotate and move longitudinally, a shaft, 6. The inner end of the shaft 6 is provided with a projection, 7, adapted to

go into an aperture in the end of the music spool. Back of the projection, 7, is an annular collar, 8, and between the collar 8 and the journal, 5, is a coil spring, 9, which tends to press the shaft, 6, inwardly, so as to engage the end of the music spool. A collar 10 is adjustably secured by a set screw, 11, to the outer end of the shaft, 6, so that it will not be entirely withdrawn from the journal, 5, by the action of the spring, 9, when the inner end of the shaft is not in engagement with the music spool.

In the upper portion of the side bar, 1, opposite to and alining with the journal, 5, I provide the mechanism clearly shown in detail in Fig. 2. The construction of this mechanism and its operation is as follows:— A journal 12 is provided in the side bar, 1, in which is mounted the shaft, 13, the inner end of which is provided with a square or angular projection, 14, which extends into and engages a cavity provided for that purpose in the end of the music spool. Back of the projection, 14, is a collar 15. Upon the inner face of the side bar, 1, and about the journal, 12, is provided a bracket, 16. Into this bracket, 16, screws the knurl headed washer, 17, the outer edge of which abuts against the edge of the collar 15. Upon the outer end of the shaft, 13, is provided suitable driving mechanism not shown.

The music spool is inserted into the above described mechanism by placing one end thereof upon the projection, 7, of the shaft, 6, and pressing the shaft outwardly against the action of the spring, 9, until the other end thereof may be brought opposite the projection, 14, upon the shaft, 13, at which time the spring 9 is permitted to become effective and press the end of the music spool into engagement with the projection, 14. The longitudinal location of the music spool is secured by the rotation of the knurl headed screw, 17, against the action of which the spool is pressed by the spring, 9.

In the lower portions of the side bars, 1 and 2, is journaled the spool 4, which receives the music roll as it is unwound from the roll to which it is permanently attached, and the bearings for this spool are such as to permit it longitudinal play so that it may follow and accommodate itself to the location of the upper spool.

Between the spools, 3 and 4, and so dis-

110

posed as to contact the music roll passing between the spools, is the tracker board, 18. This tracker board consists of two pieces, a shorter end piece, 19, which is provided with holes, 20, into which extend pins, 21, secured by screws, 22, in a longer piece, 23, of the tracker board, in which are located the note apertures, 24. A knurl headed screw, 25, is provided in the shorter piece, 19, of the tracker board, the inner end of which screws into the portion, 23, of the tracker board and which is provided with a collar, 26, abutting against the portion, 19, of the tracker board so that by rotating the 15 knurl headed screw, 25, the portion 23 of the tracker board is forced away from or drawn toward the portion, 19. The head of the screw is exposed so as to be readily accessible. It is only necessary to turn its head up 20 or down in order to adjust the parts and hold them in the adjusted position by one operation. The outer end of the tracker board portion, 23, is provided with pins, 27, which are journaled to slide longitudinally 25 in the side bar, 1, and the portion, 19, of the tracker board is carried upon a shaft, 28, journaled to slide transversely in the side bar, 2. A collar, 29, is adjustably secured to the shaft 28, by means of the set screw, 30, and between the collar 29 and the outer face of the side bar, 2, is a coil spring, 31, the action of which tends to hold the tracker board as far to the left or toward the side bar, 2, as it can be drawn. Near the end of 35 the shaft, 28, is a nut or button 32.

To the outer face of the side bar, 2, is secured a valve casing which contains a vacuum compartment, 33, communicating by means of the piping A, with the means for 40 producing the vacuum not shown. Directly below the vacuum chamber, 33, is a diaphragm chamber, 34, which is separated from the vacuum chamber by a diaphragm 35. The diaphragm chamber communicates 45 with the vacuum chamber by means of a passageway, 36, which is partially closed by a suitable strip of parchment in which there is a greatly reduced aperture or bleed hole, 37. Above the vacuum chamber, 33, is 50 a passageway, 38, leading directly to the outside atmosphere. The top and bottom of this passageway, 38, are closed by valves, 39 and 40, carried upon a single stem, 50, the lower end of which is provided with a 55 button 51, which comes directly above and closely contiguous to the diaphragm 34. A passageway, 52, leads from between the valves, 39 and 40, to the side of the casing and into a bellows, 53, secured thereto. 60 Upon the movable member 54 of the bellows 53, is secured an arm 55, which is split so as to surround the shaft 28 and contact with the nut or button 32 carried thereby. In the short end piece, 19, of the tracker board, is 65 provided an aperture, 56, which communi-

cates by means of a tube, 57, with the diaphragm chamber, 34.

The operation of the mechanism is as follows:—A music roll is inserted between the shafts, 6 and 13, and secured to the lower 70 spool, 4. The upper music roll is now adjusted by means of the knurl headed screw, 17, so that the edge of the music sheet just splits the aperture, 56, in the short end portion, 19, of the tracker board. The knurl headed screw, 25, is now rotated so as to bring the apertures 24 in the long piece, 23, of the tracker board so as to exactly register with the perforations in the music roll. When the production of the piece is started, 80 a vacuum is created in the chamber 33. The edge of the music roll as above described just coming half way across or splitting the aperture, 56, permits air to flow therethrough and through the tube 57, 85 to the diaphragm chamber, 34. This causes the elevation of the diaphragm and the elevation of the valve stem, 50, which opens the valve, 39, and closing the valve 40, thereby creating communication 90 between the bellows, 53, and the vacuum chamber 33. The atmospheric pressure collapses the bellows, 53, and through the arm 55 and button 32, the shaft, 28, is forced to the right, thereby forcing the entire tracker board comprising the pieces, 19 95 and 23, to the right. This restricts the area of opening through 56 and the volume of air flowing to the diaphragm chamber. When the area of opening through 56 is restricted to less than the area of the bleed hole 37 the diaphragm chamber will be partially exhausted through the bleed hole, 37, thereby causing the depression of the diaphragm and the closure of the valve 39 and 100 the opening of the valve 40. The spring, 31, now becomes effective and forces the shaft, 28, to the left thereby increasing the open area through the aperture, 56. The result of this condition is to cause the tracker 110 board to be balanced between the actions of the bellows, 53, and the spring, 31, thereby securing a sensitive, immediately responding automatic adjustment of the tracker board to the paths of the perforations in the music roll which have previously been carefully adjusted with relation to the edge of the aperture 56, by means of the knurl headed screw, 25.

It will now be seen that I have provided 120 a means for adjusting the apertures in the trackerboard to the perforations in the music roll so as to accommodate the usual variation in their position, and I have also provided a means for automatically causing the 125 entire tracker board to move longitudinally to meet and overcome any irregularities which may be occasioned by the uneven winding of the music roll.

There is a continuous flow of air through 130

the guide-opening and diaphragm chamber and bleed hole, the pressure in the diaphragm chamber being variable or undulatory. This feature of the apparatus, however, is not claimed broadly in the present application, being covered in a co-pending application Serial No. 695,511, filed May 6, 1912.

Having thus described my invention what I claim as new and desire to secure by Letters Patent, is:—

1. A tracker mechanism for piano players comprising a tracker board, a member in the path of the music sheet and having a single port, means controlled by the position of a single edge of the music sheet relatively to said single port for automatically shifting the lateral relation between the tracker board and said sheet in opposite directions as required to maintain them in correct register, and a device for effecting a relative lateral adjustment between the tracker board and said member.

2. A tracker mechanism for piano players comprising a single ported member over which a part of the music sheet passes, mechanism operated by the increasing of the open area of such port by the music sheet for automatically adjusting the lateral register of the sheet with the tracker board in one direction and by the decreasing of the open area of said port for automatically adjusting the register in the opposite direction, and means for causing a relative lateral adjustment between said ported member and the tracker board.

3. A tracker mechanism for piano players comprising a single ported member over

which a part of the music sheet passes, mechanism operated by the increasing of the open area of such port by the music sheet for automatically adjusting the lateral register of the sheet with the tracker board in one direction and by the decreasing of the open area of said port for automatically adjusting the register in the opposite direction, and means for causing a relative lateral adjustment between said ported member and the tracker board, said adjusting means comprising a screw exposed at the side of the sheet and adapted when turned to cause the desired adjustment.

4. A tracker mechanism for piano players comprising devices for effecting relative movement longitudinally of the tracker board between the music sheet and the tracker board, one of said devices causing such movement in a direction opposite to that caused by the other, a member in the path of said sheet and having a port, the increasing of the open area of which causes one of said devices to operate and the decreasing of the open area of which causes the other of said devices to operate, whereby the sheet is maintained in such a position as to nearly cover said port and balance said devices against each other, and means for effecting a relative lateral movement between said ported member and the tracker board.

In testimony whereof I affix my signature in the presence of two witnesses.
